WM. C. EDGE.

UNITED STATES PATENT OFFICE.

WILLIAM C. EDGE, OF NEWARK, NEW JERSEY.

DESIGN FOR A WATCH-CHAIN.

SPECIFICATION forming part of Design No. 13,875, dated May 1, 1883.

Application filed March 9, 1883. Term of patent 14 years.

To all whom it may concern:

Be it known that I, WILLIAM C. EDGE, of Newark, county of Essex, and State of New Jersey, have invented a new and original Design for a Watch-Chain, of which the following is a specification.

Figures 1, 2, and 3 represent face views of watch-chains having my new design.

This invention relates to a new configuration of chains for watch-chains and other purposes; and it consists in making the chain with projecting ribs along its face, each inner rib having a braid-like appearance, and with edge ribs formed of obliquely-placed links, the recessed portions of the face—that is, the grooves between the ribs—being made of links that are placed transversely—that is to say, at right angles to the direction of the length of the chain.

In the photographic illustration, the letter A represents my new chain. The face of the

same presents at each edge projecting ribs a and b, each of said ribs a b being composed of obliquely-placed contiguous links, as shown. On the face of the chain A, between the ribs a b, are also observable one, two, three, or more projecting ribs, c, each presenting a braid-like appearance. The grooved or sunken part of the face of the chain is composed of transversely-placed links or pieces, so as to present to the eye lines that run at right angles to the direction of the length of the chain. These grooved portions are marked d in the photograph.

I claim—

The design for a chain, having the ribs a b c and the intervening portions, d, of transversely-placed links, substantially as shown.

WM. C. EDGE.
